[57] CLAIM

The ornamental design for a beverage container, as shown and described.

DESCRIPTION

FIG. 1 is a top plan view of a beverage container showing my new design;

FIG. 2 is a side elevational view, the opposite side being a mirror image thereof;

FIG. 3 is a front elevational view;

FIG. 4 is a fragmentary rear view looking in the direction of the line 4—4 of FIG. 2;

FIG. 5 is a bottom plan view thereof; and

FIG. 6 is a fragmentary cross-sectional view taken along lines 6—6 of FIG. 5.

The rear elevations of the containers mirror images of the front elevations.

Fig. 1.Fig. 5.44Fig. 4.Fig. 2.Fig. 3.

FIG. 6
